KNOCKDOWN TOY

Harry H. Fischman and Ercole J. Manelia, Chicago, Ill.;
said Manelia assignor to said Fischman

Application January 23, 1957, Serial No. 635,626

11 Claims. (Cl. 46—22)

This invention relates to a toy and more particularly to a put together construction toy utilizing inflatable articles such as toy balloons.

One of the objects of this invention is to provide means for ready attachment to toy balloons or the like whereby a plurality of balloons may be connected together in the nature of a construction toy to form a put together built up toy object.

Another object is to provide means whereby toy balloons may be readily connected together by a child to form any number of put together built up objects, simulating construction sets used by children.

It is recognized that construction sets of various kinds and build up attaching blocks have a great fascination and educational value for children, in that by connecting the parts the child is required to use his imagination and his skill in forming various assembled put together toy objects. After the child has completed one object, the parts may be disassembled and re-arranged to form other toy objects. This invention aims to provide such a construction toy by the use of inflatable objects such as toy balloons which are relatively inexpensive as contrasted to other types of put together toys.

The child is afforded a great deal of play and educational value in constructing various objects made up of inflatable balloons in accordance with this invention. The assembled objects are relatively large due to the use of the inflatable balloons. The parts are simple and inexpensive and utilize in the main conventional toy balloons which may be readily replaced if broken or busted. Thus as contrasted with other types of construction toys which become obsolete by the loss of some of the parts, the present invention retains its play value if some of the balloons are lost or busted because they may be augmented or replaced by any conventional toy balloon purchasable in any candy or child's supply store.

Another object of this invention is to provide attaching means for toy balloons which attaching means is self contained in that it becomes a part of the balloon as long as it is attached thereto and requires no attachment to another balloon to render it effective. In other words each balloon then becomes a self contained building member and is attachable to other balloons by the use of a connector which does not affect the attaching means. Each balloon may therefore be handled separately and put together with other balloons in a manner similar to the way building blocks are handled.

Other objects will become apparent as this description progresses.

In the drawings:

Fig. 1 is a view showing a put-together toy formed in accordance with this invention.

Fig. 2 is a view showing another put-together object in the form of the letters of the alphabet.

Fig. 3 is a view of the attaching means secured to two balloons and a connector therebetween.

Figure 4 is an enlarged view partly in cross section

2

taken on lines 4—4 of Fig. 3 and showing the manner of securing the attaching means to the balloon.

Fig. 5 is an exploded perspective view of the parts constituting the attaching means.

5 Fig. 6 is a plan view of the plug member of the attaching means, and

Fig. 7 is a cross sectional view of a modified form of attaching means, and showing a modified form of ring.

The preferred form of the invention is shown in Figs.

10 1 to 6, inclusive. The inflatable toy balloon is of conventional construction purchasable on the market. Said conventional toy balloons are usually of two types, one the ball or globe type when inflated and the other the elongated type which assumes a somewhat sausage shape when inflated. These balloons which come in various sizes may be connected together in accordance with this invention to form an unlimited number and variety of assembled toy objects and then may be disassembled and detached to be used as conventional balloons if desired or to form other toy objects.

The globe or ball type of balloon is designated by the numeral 10 and the elongated sausage type of balloon is designated by the numeral 12. Obviously any other type or shaped balloon may be used.

25 The attaching means generally indicated at 14 and best shown in Figs. 4 and 5 includes a rigid ring like member generally indicated at 16 and a plug like member generally indicated at 18, both of which are formed preferably of plastic material. The opposite faces 17

30 and 19 of the ring are substantially flat. The plug member 18 which is integrally formed comprises a body portion 20 and an enlarged head 22 which is rounded as at 23 at its outer end. The head 22 is provided with intersecting slots 24 which form a cross and which appear

35 as four radially extending slots. Each of said slots continues downwardly and extends into the body portion 20 as at 26 for a portion of the length of the body. This provides the plug particularly at the head portion with a resiliency or "give" to permit compression of the head 40 when it is inserted in the ring 16 as will be described. The plug has a central longitudinal bore 28 which tapers outwardly to its largest circumference adjacent the outer end of the body.

45 To connect the attaching means 14 to the balloon, the ring 16 is inserted or dropped into the balloon (of either type) through the mouth 11 of the balloon (when in non-inflated condition) and moved to any portion of the balloon where the connection is desired to be made and positioned against the rubber on the underside of the balloon.

50 The plug 18 on the outside of the balloon is then brought into alignment with the ring 16 with the head 22 of the plug positioned and resting against the outside of the rubber of the balloon and adjacent the ring.

55 The plug is pushed inwardly into the ring head first with the rubber material around it. The head 22 of the plug thus compresses due to the slots 24 to allow the head to pass inside and through the ring, after which the head expands to surround the ring as best shown in Fig. 4. The balloon material is gathered around the head 22, the ring 16 and around a portion of the body 20 and the ring and plug are detachably locked to the balloon.

60 The plug and ring thus secured to the balloon renders each balloon and its attaching means a self-contained unit ready for immediate use. In other words, each balloon thus becomes in effect a separate self contained member available for the building of a toy object and hence does not require the joining of two balloons at the time the attaching means are applied to the balloons as is necessary in the structure of the prior art.

65 With the attaching means applied to each balloon, the

balloon is inflated in the conventional manner and the mouth of the balloon is tied or otherwise secured to retain the air therein. Each inflated balloon thus in effect becomes a separate building block and may be retained in inflated position with its respective attaching means ready for immediate use so that a plurality of balloons may be connected together in any arrangement desired merely by insertion of the connector rod to be described.

A major portion of the body of the plug 20 extends outwardly of the balloon as best seen in Figs. 3 and 4. The plug is then ready to receive one end of a connector rod or dowel generally indicated at 30. The connector rod or dowel may be of any length and is formed preferably of plastic or like material. However, wooden rods will serve with equal facility. The rod is inserted in the tapered bore 28 and will, due to the radial slots 24 and 26 in the head and body of the plug cause the body and head to "give" sufficiently to frictionally retain the rod against accidental removal. The inner tapered end of the bore 28 will limit the extent to which the rod may be inserted in the bore and the end of the connector rod 30 will not engage the rubber of the balloon to permit any puncturing thereof.

Another attaching means 14 similar to that described is connected to another balloon in the same manner, and the opposite end of rod 30 is inserted in the bore thereof to rigidly connect the two balloons together. By providing rods 30 of various lengths the spacing between balloons may be varied to permit various arrangements. Also several attaching means 14 may be connected to a balloon, for example as shown in Fig. 1 to permit a plurality of balloons to be connected in the nature of legs to form a simulated human figure or an animal figure. The balloons may be readily detached from the connector by slipping the connector rod 30 out of the plug 18 and attachments to other balloons may be made.

A few of the unlimited number of put-together toys that may be formed are shown merely by way of illustration in Figs. 1 and 2.

In Fig. 1 the lowermost connector rods 30 have their lower ends detachably and frictionally secured in suitable openings in a supporting disc or base 32 formed of cardboard or the like. If the put-together object is a toy animal with more than two legs the supporting base may be eliminated.

Fig. 2 shows a pair of the elongated type balloons 12 arranged and connected together to form the letter D of the alphabet. All the letters of the alphabet may be formed by a similar arrangement utilizing the principle of this invention.

If desired the attaching means 14 may be readily removed from any balloon by merely pulling outwardly on the plug 18 to compress the head 22 and permit its passage past the ring to unlock the ring and plug and the ring is then removed through the mouth of the balloon.

No damage is done to the balloon by the manner of securing the attaching means thereto and the attaching means may be repeatedly connected to or detached from the balloon without injury thereto. It may be readily attached to any portion of the balloon and this procedure is so simple that it may be easily done by any child and requires no training.

Fig. 7 shows a modified form of plug generally indicated at 34. The plug has a body portion 36, a reduced neck 38 and a head 40 of substantially the circumference of the body portion 36. The head is provided with four slots 42 similar to slots 24 to render the head compressible. The plug body is provided with a tapered bore 44 similar to the bore 28. The ring 16' may be identical to the ring 16 previously described or may be provided with a split 16b to render said ring slightly expandable when the head 40 is inserted therethrough. Attaching the plug 34 to the balloon is accomplished in the same manner as described in connection with Figs. 1 to 6, however in Fig. 7 the plug is locked to the ring around

the neck portion 38, with the ring positioned between the opposite shoulder 46 and 47. This modified plug is connected to connector rods identical in the manner previously described. The split ring shown in Fig. 7 is formed of a rigid material preferably of plastic and is rigid throughout as is ring 16 except that it "gives" or expands slightly due to the split portion when the head of the plug is being inserted and then assumes its pre-formed shape after the head is passed through to lock the plug and ring together in the balloon.

The split ring shown in Fig. 7 may also be used in lieu of the ring 16 in connection with the plug shown in Figs. 1 to 6 inclusive. It may be found desirable when in using the split ring shown in Fig. 7 to eliminate the slots 24 in the head 22 (Figs. 1 to 6) or the slots 42 in the head 40 and make said heads solid as the expansion or "give" of the split ring will permit the head to be inserted therein and through the ring to lock the ring and plug together.

It will be understood that various changes and modifications may be made from the foregoing without departing from the spirit and scope of the appended claims.

We claim:

1. In a toy formed of a plurality of inflatable bodies each provided with means for permitting inflation thereof, each inflated body having separate attaching means comprising a ring formed of rigid material inserted inside each said inflatable body and a separate member for each of said inflatable bodies and each separate member provided with a head engaging the outside of said inflatable body, said head being normally larger than the opening in said ring, said head being compressible and insertable in each said ring with a portion of the material of said inflatable body for locking engagement therewith to retain each said member against removal from said inflatable body, and to form with each inflatable body an inflatable unit separate and independent of the other inflatable unit, each said member having means outwardly of said inflatable body for ready connection with a connecting member to connect said inflatable bodies to form a put-together toy, each said inflatable unit being connectable to and disconnectable from said connecting member while inflated or deflated and without effecting the attachment of the attaching means to any of the inflatable units.

2. In a toy formed of a plurality of inflatable bodies each provided with means for permitting inflation thereof, each inflated body having separate attaching means comprising a split ring formed of rigid material insertable inside each said inflatable body and a member provided with a head engaging the outside of each said inflatable body, said head being normally larger than the opening in said ring and insertable in each said split ring with a portion of the material of said inflatable body by expanding said ring for locking engagement therewith to retain said member against removal from said inflatable body, and to form with each inflatable body an inflatable unit separate and independent of the other inflatable unit, each said member having means outwardly of each said inflatable body for ready connection with a connecting member to form a put-together toy, each said inflatable unit being connectable to and disconnectable from said connecting member while inflated or deflated and without effecting the attachment of the attaching means to any of the inflatable units.

3. In a toy formed of a plurality of inflatable balloons each provided with means for permitting inflation thereof, each of said balloons having separate attaching means comprising a ring inserted inside each said balloon and a plug for each of said rings having a head normally larger than the opening in said ring and provided with slots to render said head compressible when inserted in said ring, said head engaging the outside of its respective balloon and insertable in its respective ring with a

portion of said balloon for locking engagement therewith to retain said plug against removal, and to form with each balloon a balloon unit separate and independent of the other balloon unit, each said plug having a bore extending outwardly of its said balloon, a connecting rod connectable in said bores to connect the balloons together to form a put-together toy, each said balloon unit being connectable to and disconnectable from said connecting member while inflated or deflated and without effecting the attaching means to any of the balloons.

4. A toy formed of a plurality of toy balloons each provided with means for permitting inflation thereof, each said balloon having separate attaching means comprising a ring member insertable inside said balloon and a plug having a head member for insertion in said ring member, said head member being normally larger than the opening in said ring member, at least one of said members being sufficiently resilient with respect to the other to permit insertion of said head member in said ring member, said head member engaging the outside of said balloon and insertable in said ring member with a portion of said balloon for locking said balloon between said ring member and said plug, to form with each balloon a balloon unit separate and independent of the other balloon unit, each said plug having a longitudinal bore extending outwardly of its balloon, a connecting rod frictionally and detachably retained in said bores to connect the balloons together to form a put-together toy, each said balloon unit being connectable to and disconnectable from said connecting rod while inflated or deflated and without effecting the attachment of the attaching means to any of the balloons.

5. A toy formed of a plurality of toy balloons each provided with means for permitting inflation thereof, each said balloon having separate attaching means comprising a ring member insertable inside said balloon and a plug having a head and a body portion, said head being normally larger than the opening in said ring and having radially extending slots to render said head compressible for insertion into said ring, said head engaging the outside of said balloon and insertable in said ring with a portion of said balloon for locking said balloon between said ring and said plug to form with each balloon a balloon unit separate and independent of the other balloon unit, said body portion each having a longitudinally tapered bore opening outwardly of its balloon and provided with slots communicating with said bore, and a connecting rod frictionally and detachably retained in said bores to connect the balloons together to form a put-together toy, each said balloon unit being connectable to and disconnectable from said connecting rod while inflated or deflated and without effecting the connection of the other balloon unit.

6. In a toy formed of a plurality of inflatable balloons each provided with means for permitting inflation thereof, connector means connected to each said inflatable balloon whereby each said balloon forms a separate and independent self-contained unit ready for attachment to another similar self-contained balloon unit without disturbing the connector means of each balloon unit, each connector means comprising a ring insertable in the balloon and a member having a head portion normally larger than the opening in said ring, said head portion being sufficiently resilient to permit insertion of said head portion in said ring, said head portion engaging the outside of the balloon and insertable in said ring for locking engagement therewith to retain said member against removal from said balloon, and connecting means connected to said members for joining said inflatable balloon units to form a put-together toy, said balloon units each being connectable to and disconnectable from said connecting means while inflated or deflated and without effecting the connection of the other balloon unit.

7. In a toy formed of a plurality of toy balloons each balloon having a body portion and a mouth opening for permitting inflation and deflation thereof, each balloon having separate attaching means comprising a first member and a second member, said first and second members being so constructed to provide resiliency between said members to permit passage of said second member into said first member, said first member insertable inside said body portion through said mouth opening and adapted to engage the inside of the imperforate wall of said body portion, said second member engaging the outside imperforate wall of said body portion and adapted to interlock with said first member and gather a portion of said imperforate wall therebetween to retain said first and second members against removal and to form with each balloon a balloon unit separate and independent of the other balloon unit, said second members each extending outwardly of its balloon and each having a connecting end, means for connecting said connecting ends to connect said balloons together to form a put-together toy, each said balloon unit being connectable to and disconnectable from the other balloon units while inflated or deflated and without effecting the attachment of the attaching means to any of the balloons.
8. In a toy formed of a plurality of toy balloons each balloon having a body portion and a mouth opening for permitting inflation and deflation thereof, each balloon having separate attaching means comprising a first member and a second member, said first member insertable inside said body portion through said mouth opening and adapted to engage the inside of the imperforate wall of said body portion, said second member engaging the outside imperforate wall of said body portion and adapted to interlock with said first member and gather a portion of said imperforate wall therebetween to retain said first and second members against removal and to form with each balloon a balloon unit separate and independent of the other balloon unit, said second members each extending outwardly of its balloon and each having a connecting end, a connecting member secured to said connecting ends to connect said balloons together to form a put-together toy, each said balloon unit being connectable to and disconnectable from said connecting member while inflated or deflated and without effecting the attachment of the attaching means to any of the balloons.
9. In a toy formed of toy balloons each balloon having a body portion and a mouth opening for permitting inflation and deflation thereof, each balloon having separate attaching means comprising a first member and a second member, said first and second members being so constructed to provide resiliency between said members to permit passage of said second member into said first member, said first member insertable inside said body portion through said mouth opening and adapted to engage the inside of the imperforate wall of said body portion, said second member engaging the outside imperforate wall of said body portion and adapted to interlock with said first member and gather a portion of said imperforate wall therebetween to lock said first and second members against removal and to form with each balloon a balloon unit separate and independent of the other balloon unit, said second member having a bore opening outwardly of its balloon, a separate connecting rod having its opposite ends attachable in the bores of two balloon units when inflated for assembling a put-together toy, each said balloon unit being detachable from said connecting rod while inflated or deflated without effecting the attachment of the attaching means to any of the balloons.
10. In a toy formed of toy balloons each balloon having a body portion and a mouth opening for permitting inflation and deflation thereof, each balloon having separate attaching means comprising a ring and a plug having a head, said ring and said head being so constructed to provide resiliency therebetween to permit passage of

said head into said ring, said ring insertable inside said body portion through said mouth opening and adapted to engage the inside of the imperforate wall of said body portion, said head engaging the outside imperforate wall of said body portion and adapted to pass into said ring to interlock with said ring and gather a portion of said imperforate wall therebetween to retain said ring and plug against removal and to form with each balloon a balloon unit separate and independent of the other balloon unit, means between said plugs for detachably connecting said plugs together when said balloons are inflated for assembling a put-together toy, each said balloon unit being detachable from the other balloon unit while inflated or deflated and without effecting the attachment of the attaching means to any of the balloons. 15

11. In a toy formed of a plurality of toy balloons each balloon having a body portion and a mouth opening for permitting inflation and deflation thereof, each balloon having separate attaching means comprising a first member and a second member, said first member having an opening therein and insertable inside said body portion through said mouth opening and adapted to engage the inside of the imperforate wall of said body portion, said second member having a head insertable in said opening and engaging the outside imperforate wall of said body portion and adapted to interlock with said first member 25

5 and gather a portion of said imperforate wall therebetween to retain said first and second members against removal and to form with each balloon a balloon unit separate and independent of the other balloon unit, said second members each extending outwardly of its balloon and each having a connecting end, means for connecting said connecting ends to connect said balloons together to form a put-together toy, each said balloon unit being connectable to and disconnectable from the other balloon units while inflated or deflated and without effecting the attachment of the attaching means to any of the balloons.
